CLOTHESPIN

Ernest Albert Alsop and Harold Victor King,
Melbourne, Victoria, Australia

Application October 18, 1946, Serial No. 704,070

9 Claims. (Cl. 24—137)

1

This invention relates to an improved clothes pin and it refers particularly to a clothes pin of that type wherein two members are pivotally fitted together and are held in position by a coil spring which is adapted to oppose any opening action such as when the clothes pin is fitted to clothes suspended on a clothes line.

It is an object of the invention to provide a clothes pin, particularly suited for production by plastic moulding operations, which is of simple and inexpensive construction while being of sturdy design; which is of extremely attractive appearance; which is so made that the two cooperable members of said clothes pin will be restrained against relative lateral movement, and which is of convenient size for packaging purposes.

With these and other objects in view we have constructed a clothes pin comprising two elongated body members held together in pivotal arrangement by means of a coil spring, the opposite ends of which are formed as intwined arms to bear upon the outer sides or surfaces of said body members at predetermined locations thereof. The coil spring is housed within two upper recesses in the head portions of the said body members and the clamping jaw or leg portions of said body members have their inner surfaces flared, to provide a lead to enable the clothes pin to be slid smoothly over clothes suspended on a clothes line, and recessed to ensure that the clothes pin will firmly grip said clothes so as to hold them securely on the clothes line. Each of the body members is formed with a longitudinal groove and, adjacent thereto, a tongue or rib. Said groove and said tongue are so located and so dimensioned that when the two body members are fitted in assembled condition the tongue of the one interfits or engages with the groove of the other, and vice versa. Consequently, relative lateral movement between said body parts or members is effectively prevented. The two body members are of identical construction so that, when they are moulded in plastic materials, only one die is required for their production.

In order that the invention will be clearly understood reference will now be made to the accompanying drawing, wherein:

Fig. 1 is a perspective illustration of a clothes pin constructed according to this invention.

Fig. 2 shows, in side elevation, the inner surface of one of the body members of the clothes pin.

Fig. 3 is a horizontal section on the line and in the direction of the arrows 3—3 of Fig. 2.

Fig. 4 shows a transverse section through the

2

clothes pin, the section being taken as on the line indicated by the arrows 4—4 of Fig. 2.

Fig. 5 is a similar section showing the clothes pin opened a relatively large amount.

5 The clothes pin illustrated in these drawings comprises two body members or parts 1A and 1B, each of which has at its upper end a head 2 and at its lower end a clamping jaw or leg 3. The outer surface of the head 2 tapers outwardly and upwardly, forming a neck 4, which provides a convenient finger grip, and at an intermediate position the body is formed with a hip 5 which is grooved or recessed at 6. The leg 3 is formed with a strengthening rib 7 on its outer surface and at its lower end it is curved outwardly at 8.

10 The inner surface of each body member 1A or 1B is formed with a first inner transverse arcuate recess 9 and with a second inner transverse recess 10. Between said recesses 9, 10, a vertical longitudinal groove 11 and an adjacent, vertical longitudinal tongue or rib 12 are arranged to extend at either side of the longitudinal center line of each body part. The said groove 11 and tongue 12 are substantially coextensive with respect to each other and are spaced substantially equal distances from the opposite side edges of the body members 1A and 1B, the groove 11 of each body member 1A or 1B being of such length, breadth and depth that the tongue 12 of the opposed body member 1B or 1A fits neatly thereinto. A side wall defining groove 11 is aligned with or forms a continuation of an adjacent side wall defining tongue or rib 12 (Figs. 2 and 3). The two body members are, as near as practicable, of identical construction, being adapted to be produced with one and the same mould.

15 When the inner transverse recess 9 is formed in the head 2 there is provided a small lip or abutment 13, for the purpose to be hereinafter described.

20 A coil spring 14 is housed within the recesses 9 of the assembled body members 1A, 1B—said recesses being of slightly larger radius than said spring 14—and the opposite ends of said spring 14 are formed as arms 15. The outer ends of said arms 15 are inturned at 16 and when the spring is correctly fitted in the recesses 9 those inturned ends are adapted to seat within the outer transverse recesses 6 provided in the outer surfaces of said body members. The spring 14 is so made that the inturned ends 16 exert inwardly directed pressure on the body members 1A, 1B so that they are restrained against pivotal opening movement.

25 To assemble the parts of the clothes pin the

two body members are placed fore to fore so that the tongue 12 of each is neatly seated in the groove 11 of the other. The inturned ends 16 of the spring 14 are then slid over the upper ends of the head portions 2. The lower ends of legs 3 forming clamping jaw sections of the clothes pin may be opened apart—thereby closing the upper ends 2—to enable that to be done expeditiously. The coil spring 14 is finally slid into position within the recesses 9, when the inturned ends of said spring are seated firmly in the recesses 6. The upper ends 4 of the body legs 3 forming guide sections of the members 1A, 1B will be opened a short distance as the spring 14 moves past the lips 13.

When the clothes pin is so assembled—as shown in Fig. 4—with the pressure of the spring 14 holding the guide sections and clamping jaw sections of the body members 1A, 1B together, the lips 13 will be spaced a short distance apart and each of the tongues 12 will be seated snugly in the opposed groove 11 so that relative lateral movement at said guide sections of the clothes pin will be positively prevented.

If, then, the clothes pin is slid over an article of clothing suspended from a clothes line—the outwardly flared ends 8 of the clamping jaw sections of the legs 3 permitting an easy sliding movement—the two cooperable, elongated body members 1A, 1B will be moved pivotally apart, pivoting about an axis slightly below the coil spring 14, until the two lips or abutments 13 meet. As illustrated in Fig. 5 of the drawings, the opposite tongue and groove connections remain always interengaged at their upper ends and relative lateral movement will still be prevented.

It will be found that the clothes pin manufactured according to this invention will be of extremely attractive appearance, sturdy and durable in use and will possess the advantages that the two body parts will not come apart by lateral movement under normal working conditions. Moreover, as the two body parts are of similar design and construction it will advantageously be produced in large quantities by mass production methods. The advantage of assembling two parts of the same shape as compared with the assembling of two parts of different shape is readily apparent.

The tapering head 2 of each body member provides a convenient finger grip for the manipulation of the pin which is normally employed as a "push on" clothes pin. If desired the legs 3 of the pin may be opened by applying finger pressure to the head of the pin. This will be of advantage when the clothes pin is used with delicate fabrics. Consequently the clothes pin made according to our invention combines the advantages of the "push on" clothes pin—convenience in packaging—with the advantages of the "openable" clothes pin.

Having thus described the invention, what is claimed as new and desired to be secured by Letters Patent, is:

1. A clothes pin comprising a first elongated body member, a second elongated body member, spring means fitted between said body members and having its opposite ends formed as arms adapted to bear upon the outer surfaces of said body members and thereby restrain said body members against pivotal opening movements about said spring means, each body member being provided with a longitudinal groove in its inner surface and a longitudinal tongue adjacent

said groove, said grooves and said tongues extending between said pivot forming spring means and the opposite ends thereof, the tongue of the first body member being adapted to seat in the groove of the second body member and the tongue of the second body member being adapted to seat in the groove of the first body member whereby relative lateral movement of said body members is prevented.

10 2. A clothes pin comprising two elongated body members, spring means fitted between said body members near the upper ends thereof, each of the body members including an upwardly and outwardly tapering head portion, a transverse recess in the inner surface of said head portion for retaining said spring means, a longitudinal groove and an adjacent longitudinal tongue on the inner surface of said head portion coextending lengthwise of the latter and below said transverse recess, a hip on the outer surface of said body member below said head portion, a transverse recess in said hip for accommodating the ends of said spring means, respectively, and a clamping jaw portion extending below said hip.

20 3. A clothes pin according to claim 2, wherein said longitudinal grooves and said tongues extend between said transverse recesses of said head portions and the transverse recesses provided in the hips of said body members.

4. A clothes pin comprising two interfitting opposed body members, a coil spring having free ends and forming a pivot for said body members in assembled condition thereof, each of said body members comprising a head portion, a hip portion and a leg portion; the head portion having its outer surface of outwardly and upwardly tapering formation and having at its inner surface a transverse recess for seating said coil spring, a longitudinal groove and an adjacent longitudinal tongue formed in the inner surface; the hip portion having a transverse recess on its outer surface for accommodating the free ends of said coil spring; and the leg portion having its lowermost end flared outwardly.

45 5. A clothes pin according to claim 4, including a lip formed on the inner surface of each head portion above the transverse recess thereof.

6. A clothes pin structure comprising a pair of elongated identical body parts each having oppositely disposed outer surface and inner surface; a guide section, a clamping jaw section, both said sections extending lengthwise of said inner surface of each body part, a first inner transverse recess at one end of each guide section, a second inner transverse recess at the opposite end of each guide section and positioned intermediate said guide section and said clamping jaw section, an outer transverse recess disposed on each outer surface of said body part and positioned at a location between said first inner transverse recess and said second inner transverse recess, each guide section being provided at its inner surface with a longitudinal rib and adjacent thereto with a longitudinal groove, said rib and said groove being arranged to extend at either side of the longitudinal center line of said body part and being substantially coextensive with each other, said body parts in assembled condition facing each other with said inner surfaces and interengaging each other by means of said ribs and said grooves, respectively, and spring means accommodated in said first inner transverse recesses and terminating in ends, respectively, accommodated in said outer transverse recesses to normally maintain said clamp-

ing jaw sections in abutting relation to each other, said spring means in said first inner transverse recesses forming a pivot for and said guide sections remaining interengaged during movements of said clamping jaw sections to open and closing positions, respectively.

7. A clothes pin structure comprising a pair of elongated identical body parts each having oppositely disposed outer surface and inner surface, a guide section, a clamping jaw section, both said sections extending lengthwise of said inner surface of each body part, an inner transverse recess at one end of each guide section, an outer transverse recess disposed on each outer surface of said body part and positioned at a location below said inner transverse recess, each guide section being provided at its inner surface with a longitudinal rib and adjacent thereto with a longitudinal groove, said rib and said groove being arranged to extend at either side of the longitudinal center line of said body part and being substantially coextensive with each other, said body parts in assembled condition facing each other with said inner surfaces and inter-engaging each other by means of said ribs and said grooves, respectively, and spring means accommodated in said inner transverse recesses and terminating in ends, respectively, accommodated in said outer transverse recesses to normally maintain said clamping jaw sections in abutting relation to each other, said spring means in said inner transverse recesses forming a pivot for and said guide sections remaining interengaged during movements of said clamping jaw sections to open and closing positions, respectively.

8. A clothes pin structure comprising a pair of elongated identical body parts each having oppositely disposed outer surface and inner surface, a guide section, a clamping jaw section, both said sections extending lengthwise of said inner surface of each body part, an inner transverse recess at one end of each guide section, an outer transverse recess disposed on each outer surface of said body part and positioned at a location below said inner transverse recess, each guide section being provided at its inner surface with a longitudinal rib and adjacent thereto with a longitudinal groove, said rib and said groove being arranged to extend at either side of the

35

40

45

50

longitudinal center line of said body part and being substantially coextensive with each other, said body parts in assembled condition facing each other with said inner surfaces and interengaging each other by means of said ribs and said grooves, respectively, and spring means accommodated in said inner transverse recesses and terminating in ends, respectively, accommodated in said outer transverse recesses to normally maintain said clamping jaw sections in abutting relation to each other, said spring means in said inner transverse recesses forming a pivot for and said guide sections remaining interengaged during movements of said clamping jaw sections to open and closing positions, respectively, and abutment means arranged at said inner transverse recess of each body part to restrict movements of said body parts during opening thereof.

9. In a clothes pin structure, a pair of elongated body parts arranged for relative movement with respect to each other, each body part having an inner surface, each inner surface being provided with a longitudinal groove and an adjacent longitudinal tongue projecting from said inner surface therebeyond, a side wall defining said groove being aligned with a side wall defining said adjacent tongue, and spring pivot means connecting said body parts with each other and with their inner surfaces in face-to-face relation, the groove and tongue of one of said body parts engaging the tongue and groove of the other body part.
